CLAIM

The ornamental design for a mini channel extender apparatus, as shown and described.

DESCRIPTION

FIG. 1 is a perspective view of a mini channel extender apparatus embodying the new design;
FIG. 2 is a top plan view of the apparatus;
FIG. 3 is a bottom plan view of the apparatus;
FIG. 4 is a right side elevational view of the apparatus;
FIG. 5 is a left side elevational view of the apparatus;
FIG. 6 is a front end elevational view of the apparatus as taken along line 6—6 of FIG. 4;
FIG. 7 is a rear end elevational view of the apparatus as taken along line 7—7 of FIG. 4;
FIG. 8 is a cross sectional view of the apparatus taken along line 8—8 of FIG. 5; and,
FIG. 9 is a cross sectional view of the apparatus taken along line 9—9 of FIG. 5.

FIG. 2

FIG. 3
